BOBBIN

Arthur L. Jackson, West Asheville, N. C., assignor
to American Enka Corporation, Enka, N. C., a
corporation of Delaware

Application August 12, 1940, Serial No. 352,333

4 Claims. (Cl. 242—111)

This invention relates to the manufacture of rayon according to the bobbin spinning process and more particularly is concerned with a process and apparatus for preparing packages of rayon yarn which will respond uniformly to after-treatment.

In the manufacture of rayon by the employment of the bobbin spinning process, it is now the practice to collect on a perforated bobbin freshly spun yarn as it issues from a spinning bath, this collection being continued until a package of suitable size has been wound. Upon completion of the winding of such a package, the yarn body, while on the spinning bobbin, is subjected to certain after-treatments such as washing, desulphurizing, bleaching and drying. After drying, the yarn is subjected to twisting and incident to that operation is rewound in a form suitable for use in the manufacturing process for which the finished thread is intended.

While the process outlined above is rather extensively employed and has met with considerable commercial success, it has been noted that the resultant yarn is not entirely perfect due to the fact that, in drying the yarn packages, those convolutions of thread nearest the rigid bobbin are unable to contract to the same extent as the outer layers of yarn, this failure resulting in undesirable non-uniformity in the final product.

To overcome the disadvantages incident to non-uniform shrinkage resulting from drying the yarn while it is still interiorly supported by the spinning bobbin, it has been proposed to wind the freshly spun yarn on a bobbin which may be reduced in diameter so that the package as a whole can be readily removed therefrom and dried, in unsupported condition, by means now used in conjunction with yarn produced according to the centrifugal bucket spinning method. In other words, it was deemed desirable to dry rayon yarn without an interior support and yet to spin the yarn according to the bobbin method. The employment of collapsible bobbins to accomplish this end has come into wide experimental use. However, because of disadvantages in the methods and apparatus now known, commercial use of collapsible bobbins has been quite limited.

One collapsible bobbin which is now known to the art is described in British Patent 359,435. The use of this bobbin, however, is not commercially feasible for the reason that the doffing of the bobbin from the machine, the subsequent collapsing thereof, the removal of the package therefrom by hand, the re-expansion of the spool

and the replacement thereof on the machine involves too many time and labor consuming manipulations. Furthermore, the bobbin shown in this patent is radially retractile to a uniform extent throughout its length so that in order to effect the removal of the wound package therefrom, it is frequently necessary that the package come into direct contact with the hand of the operator. This results in frequent displacements of and injuries to various convolutions of yarn. Such handling is therefore likely to so damage the package as to offset the very advantages sought by divorcing the yarn body from the bobbin before effecting after-treatment.

Another type of collapsible spool now known is shown and described in German Patent 583,273. This bobbin overcomes some of the disadvantages of the spool disclosed in the British patent insofar as avoiding uniform contraction throughout its length is concerned. On the other hand, the spool shown in the German patent is so constructed and arranged that the means for causing the contraction thereof will engage and interfere with the interior convolutions of thread of the package as the package is being doffed therefrom so that handling is again necessary. Furthermore, the bobbin of the German patent is operated through a peripheral drive so that both hands of the operator are employed in removing the same from the machine and removal from the machine does not automatically result in the release of interior tension. On the other hand, the means for expanding the spool must be removed from engagement with the same as a separate step additional to the removal of the bobbin from the machine with incident loss of time coupled with the possibility that shrinkage may occur before interior tension is released.

A further disadvantage in operation resulting from the employment of the collapsible bobbin shown and described in the German patent aforesaid results from the fact that the longitudinally extending radially retractile thread supporting slats are not guided in retraction and therefore must be realigned before the bobbin can be re-expanded and again inserted on the spinning machine.

It is an object of this invention to overcome all of the foregoing disadvantages and to permit the production of rayon by the bobbin spinning process which rayon may be subjected to after-treatment in the absence of interior support while at the same time the package produced will be substantially unimpaired by the removal of the interior support therefrom.

By employment of this invention it is contemplated that the removal of the spinning bobbin from the spinning machine will automatically effect the release of interior tension on the wound package.

An additional object of the present invention is the provision of a contractible spool constructed of acid and alkali-resistant materials such as lacquered aluminum and having a minimum of moving parts, the diameter of which being variable to facilitate removal of the threaded package.

Another object of the invention is the provision of a contractible bobbin from which a thread package may be removed for subsequent treatment without any manual handling of the package whatsoever and with a minimum effort on the part of the operator.

Other objects and advantages of this invention will be apparent from a consideration of the following detailed description of a preferred form thereof in conjunction with the annexed drawing wherein:

Figure 1 is a view in side elevation of a collapsible wound package support constructed according to this invention;

Figure 2 is an end view of the package support showing the manner of mounting the yarn contacting elements;

Figure 3 is a view in side elevation of a bobbin holder adapted to coact with the package support shown in Figure 1; and

Figure 4 is a side view, partially in section, of the bobbin holder and package support in cooperative relationship.

Referring particularly to Figures 1 and 2 of the drawing it will be seen that the package supporting bobbin includes a hollow cylindrical core 1 provided with spaced axially extending slots 2 about its periphery. An annular head 3 is attached to one end of the core, this head being provided with radially extending slots 4 for the reception of the ends of slats 5. Slats 5 are arranged about the periphery of core 1 and extend from the point of attachment to head 3 to a point beyond the other end of the core. It will be noted that each slat is provided with a semicircular notch 6 which will overlie the lower defining edge of the slot 4 in which it is mounted. By this arrangement each slat is mounted for movement about a point of pivot so that the slats are subject to movement in radial paths toward and away from core 1. Each of the slats 5 is generally flat while the surface nearest core 1 tapers somewhat to a point adjacent the end of the core and thereafter again broadens. Each slat is provided with a projection 7 which is adapted for free radial movement into its respective slot 2, the slot and projection combination serving to guide the movement of the slats and thus prevent any substantial lateral displacement thereof. The surface of each slat opposite the tapering surface is straight and it is the straight surface on which the yarn is wound. In order to reduce the effective diameter of the package support, a resilient ring 8, of rubber or the like, is passed around depressed portions in all of the slats 5 at a point closely adjacent head 3. This ring urges the slats radially inwardly to the position shown in Figure 1, and keeps the notch of each slat in engagement with the respective defining edge of slot 4 at all times.

The package supporting device just described is used in conjunction with a bobbin holder 9 which is attached by set screw 10 for rotation

with bobbin spindle 11 of a conventional spinning machine not shown. Bobbin holder 9 consists of a portion 12 of relatively large diameter and a portion 13 of lesser diameter. Portion 13 is provided with two annular grooves 14 and 15 and a resilient ring 16, seated in groove 14, but adapted to seat in either of the grooves and to move axially therebetween.

When the apparatus described is used in a winding operation, a spool puller of conventional construction is inserted into core 1 from the end thereof having head 3 thereon. The core 1 is then urged axially over portion 13 of bobbin holder 9 until the shoulder 17 of portion 12 is engaged. (See Figure 4.) This movement of core 1 causes ring 16 to roll from groove 14, in which it is located prior to the attachment of core 1, to groove 15 which is the driving position shown in Figure 4. By mounting ring 16 in this manner it will be seen that insertion of core 1 over portion 13 is facilitated by the movement of the ring, while the final position of the ring makes a good frictional driving connection between bobbin holder 9 and core 1. Furthermore, the force of compressed ring 16 on the sloping wall of groove 15 forces and holds the core 1 against shoulder 17 of portion 12.

While core 1 is passing over portion 13 of bobbin holder 9, the free ends of slats 5 are similarly urged over portion 12 thereof. Portion 12 thus acts as a cam to spread the slats radially outwardly against the action of resilient ring 8 to a position where the yarn contacting surface is parallel to the axis of core 1 as shown in Figure 4.

When the package holder and bobbin holder are thus connected, the spool puller is removed from core 1 and spindle 11 is caused to rotate thereby driving bobbin holder 9, core 1 and the slats 5 attached thereto. Yarn issuing from a spinning bath is then wound on the slats 5 until a package of suitable size has been made. Then a spool puller is again inserted in the end of core 1 having head 3 thereon and the package support is withdrawn axially from the bobbin holder. This action again moves ring 16, this time back to the position shown in Figure 3, while the removal of the support of portion 12 of bobbin holder 9 from between the free ends of slats 5 causes them to contract under the action of ring 8 to the position of Figure 1. The operator then merely holds the package support with the free ends of slats 5 pointing downwardly and the package will fall by gravity into a collection container or support. It should be noted that the collapse of the package support is entirely automatic and is a necessary incident to the removal of the core 1 from portion 13 of bobbin holder 9. Furthermore, because of the fact that projections 7, cooperating with slots 2, act to guide the slats 5 in their radial movement, it is never necessary to position by hand the various slats in order to permit the package holder to be replaced over bobbin holder 9. The inward radial movement of slats 5 is limited by core 1 and in this connection it should be noted that their radial movement inwardly is never so great as to permit the inner convolutions of a wound package to contact core 1 and thus so increase the friction surface between the package and core as to interfere with doffing by gravity.

Having now described the invention in its preferred form, it is understood that variations and modifications may be made therein without de-

parting from the spirit of the invention, and it is desired that the scope thereof be limited only by the spirit of the appended claims.

What is claimed is:

1. In apparatus for winding freshly formed rayon yarn, a winding spindle adapted to be driven, a bobbin holder mounted on said spindle for rotation therewith, said bobbin holder including a portion of large diameter and a portion of small diameter, a bobbin core detachably connected to said portion of small diameter, radially retractible axially extending slats arranged about the outer periphery of said core, said slats constituting a support for a wound package, means for pivotally supporting each of said slats at the end of said core remote from the portion attached to the bobbin holder, the free ends of said slats extending beyond the end of the core and overlying the portion of said holder of large diameter and held in radially extended position thereby, and means for urging said slats radially inwardly, whereby when the core is detached from the bobbin holder the slats will move radially inwardly to form a conical thread supporting surface and relieve tension on the interior of the package, at the same time permitting doffing thereof without disturbance of any of the convolutions of yarn.

2. In apparatus for winding freshly formed rayon yarn, a winding spindle adapted to be driven, a bobbin holder mounted on said spindle for rotation therewith, said bobbin holder including a portion of large diameter and a portion of small diameter, a bobbin core quick-detachably connected to said portion of small diameter, radially retractible axially extending slats arranged about the outer periphery of said core, said slats constituting a support for a wound package, means attached to said core for pivotally supporting each of said slats at the end of said core remote from the portion attached to the bobbin holder, the free ends of said slats extending beyond the end of the core and overlying the portion of said holder having a large diameter and held in radially extended position thereby, and resilient means adjacent the point of pivot of said slats for urging the same radially inwardly, whereby when the core is detached from the bobbin holder the slats will move radially inwardly to relieve tension on the interior of the package, at the same time permitting doffing thereof without disturbance of any of the convolutions of yarn.

ally inwardly to relieve tension on the interior of the package, at the same time permitting doffing thereof without disturbance of any of the convolutions of yarn.

5. 3. A collapsible bobbin for winding strand material comprising, a cylindrical bobbin core, radially retractible longitudinally tapered slats arranged about the outer periphery of said core, means for pivotally supporting each of said slats at one end of said core, the free ends of said slats extending beyond the end of said core, a bobbin holder cooperating with the free ends of said slats to urge the same radially outwardly about said points of pivot and with said core to support the same for rotation, said core limiting the extent of retraction of said slats, and means adjacent said points of pivot for urging said slats radially inwardly, whereby when the core is detached from the bobbin holder the slats will move radially inwardly to relieve tension on the interior of the package, at the same time permitting doffing thereof without disturbance of any of the convolutions of yarn.

4. In apparatus for winding freshly formed rayon yarn, a winding spindle adapted to be driven, a bobbin holder mounted on said spindle for rotation therewith, said bobbin holder including a portion of large diameter and a portion of small diameter, a bobbin core quick-detachably connected to said portion of small diameter, radially retractible axially extending slats arranged about the outer periphery of said core, said slats constituting a support for a wound package, means for pivotally supporting each of said slats only at the end of said core remote from the portion attached to the bobbin holder, the free ends of said slats extending beyond the end of the core and overlying the portion of said holder having a large diameter and held in radially extended position thereby, means for guiding said slats in their path of radial movement, and means for urging said members radially inwardly, whereby when the core is detached from the bobbin holder the slats will move radially inwardly to relieve tension on the interior of the package, at the same time permitting doffing thereof without disturbance of any of the convolutions of yarn.

ARTHUR L. JACKSON.
